WATCH-SHAPED GOLF-SCORER

Georges Jeanneret, St. Imier, Switzerland

Application December 11, 1931, Serial No. 580,387,
and in Germany December 17, 1930

5 Claims. (Cl. 235—117)

The present invention relates to improvements in watch-shaped scorers for the game of golf; said scorers having a dial with pointer and a circular series of small windows disclosing the numerals of radially arranged numeral wheels adjusted by means of an operator pin.

The novel feature of the invention consists in that the radially arranged numeral wheels are mounted in perpendicular planes on a scoring plate and have their arbors in a concentrical groove with regard to the center arbor; and in that the restoring of the zero position of the numeral wheels is effected by means of pawls, the axes of which are formed of a wire ring resting within a concentrical groove with regard to the center arbor.

The accompanying drawings represent a working example of the object of the invention. Figures 1 and 2 are front views of the scorer with the dial removed.

Fig. 3 is a rear view.

Fig. 4 is a section on the axis of the operator pin formed like a pusher pin and in the plane of the numeral wheels,

Fig. 5 is a similar section in the plane of the pointer arbors with certain parts omitted,

Fig. 6 is a section through the device for restoring the zero position and

Fig. 7 is a plan view of the dial.

The scorer possesses a circular crown-shaped base plate 1 formed with 18 slots 2 cut perpendicularly into the plate face and enclosing as many numeral wheels 3. The arbors 4 of these wheels are held fast by means of screws 90 within a groove 4² cut out from the base plate concentrically to the axis of the scorer so that the exact position of said wheels is secured. Star wheels 5 engaged by a star spring 5 are also connected fast to the wheels 3. Each numeral wheel is combined with a heart-cam 6 cooperating with a hammer 7. The hammers of all the wheels are mounted on a wire ring 8 forming the axles of the same. This wire is seated and held fast by screws 10 in a groove cut into the projecting parts formed by the slots 2 and is arranged concentrically to the pointer arbor while the hammers are held in their position on the wire within said slots by means of stop collars 9. The stop collars serve to maintain the hammers 7 in proper position (see Fig. 3).

A bridge 11 is fixed to the base plate forming the bearing member of an operator pin 12 which has an axial play limited by a screw 13 and ends with a squared portion carrying a pinion 14 geared with a gear wheel 15. This wheel 15 is

concentrical with the base plate and screwed fast by means of three screws 17 to the front side of a collar 16 having on its back side a so called restoring plate 18 fixed by means of three screws 17' engaged into the same holes as the screws 17 (Fig. 4).

On the shoulder 19 of plate 1 concentrically arranged with regard to the axis of the scorer is fastened a ratchet wheel 20 which is engaged by a resilient pawl 21 attached to the plate 18. This ratchet wheel determines and fixes the successive positions of the disk operating device for each disk 3 of the scoring mechanism. These positions are indicated on the dial 22 by the pointer 23 fast to the arbor 24. This arbor is mounted in the collar 16 and is rigidly connected with this collar and connected by a squared portion with the plate 18 and secured by a screw 25.

On the shoulder 26 of the base plate is seated loosely a crown wheel 27 which carries a pin 28 extended through a cut-out 29 of the base plate. The crown wheel will be always restored into the same position by a spring 30 sunk into a concentrical recess 31 of the base plate 1 of the scorer. The spring 30 (Fig. 1) engages the pin 28. The crown wheel 27 can only swing to a given angle because it is worked by a link 32 hinged to a pivot pin 33 which is fastened to lever 34 pivoted on the screw 35.

The operator pin 12 controls therefore this lever 34 and causes a swinging movement of the crown wheel 27 by means of the link 32 and of the pin 28. Link 32 and lever 34 will be displaced thereby on the plate 37 which is rigidly fast to the base plate. The gear wheel 15 carries an annular cam disk 38 which serves two purposes. One purpose is that it helps the axial displacing of the pin 12 when the pointer 23 points to zero. To this end the lever 34 carries a pin 40 pushing across the plate 37 against a cam 41 of the disk 38 (Figs. 2 and 4). The other purpose is that the annular disk 38 cooperates with the zero position restoring device which will be explained later on. On the bottom side of the restoring plate 18 a swivel 45 is pivoted at the point 44 (Fig. 3). An arm 47 being linked at the point 46 to this swivel carries a pin 48 bearing constantly on the crown wheel 27 under the effect of the spring 49. This spring bears on a screw head 50 on the swivel 45 and besides the pressure exerted on the swivel 45 it will also press arm 47 with pin 48 against crown wheel 27.

A pawl 51 slidably held within a stirrup 83 follows the movements of the swivel 45 as it is taken along by a 110

pin 52 engaged by the forked end of the swivel (Fig. 3).

This pawl causes, when the stem 12 is pressed upon, the rotating of the numeral wheels 3 by engaging the ratchet teeth 4¹. The movement of said pin is thus transmitted to the respective numeral wheels by means of the parts 34, 32, 28, 27, 48, 47 and 45. The pin 48 is therefore moved by the teeth of the crown wheel 27 and is successively taken along at each stepping from one numeral wheel to the next.

When the restoring plate 18 revolves around the axis 24 of the scorer, its cam edge 54 engages the heart hammers 7. This initiates movement of the heart wheels. Final movement of the heart wheels to zero position is effected by spring 55. By one simple pressure of a hammer upon any portion of the heart this heart will at once be turned and restored to its position of rest shown in Fig. 2. This is due to the particular form of the heart. The hammers 7 as seen in Fig. 4 project with their tails somewhat over the under surface of the plate 1 and are struck by the spring 55 of the restoring plate 18 when the stem 12 is turned all around. Spring 55 will swing the hammers successively against the hearts 6 so as to restore the zero position of all the wheels 3. Fig. 2 illustrates the mechanism for working the pointers 56 and 66. This mechanism works as follows:

The swivel 57 hinged by means of the pin 58 to the lever 34 causes the feeding of the wheel 59 by one tooth at each axial movement of the operator pin 12. The wheel 59 is prevented from any accidental rotation by the spring 60. The ratchet wheel 61 with the spring 62 is provided for enforcing that the operator pin be always pushed in completely. When this pin is withdrawn the point of the swivel 57 moves outside of the circumference of the wheel 59 and falls into the next tooth under the effect of the spring 63. A heart-cam 69 is combined with the wheel 59 for restoring the zero position and to the arbor of this wheel is fixed the pointer 66 for the units.

The intermediate wheel 64 carries a finger 65 which at each revolution of the wheel and under the influence of the spring 84 turns by one tooth the wheel 67 which carries on a cannon 68 the pointer 56 for the tens. With this wheel 67 is combined a heart-cam 69¹ for restoring the zero position. The restoring of the zero position of the wheels 59 and 67 is effected by the hammer 70 pivoted on the arbor 71 when the pin 72 fixed to said hammer falls into the notch 73 of the cam disk 38 under the effect of the spring 74 engaging the pin 75. The disk 38 lifts again this hammer at the beginning of each counting.

The wheel 59 as also the intermediate wheel 64 are arranged revolvably on a bridge 76 screwed fast to the plate 37.

While restoring the zero position of the hearts 69, 69¹ the hammer 70 with a beveled edge 79 which glides under the arbor 64¹ of the wheel 64 will lift simultaneously this wheel so that the finger 65 is enabled to sweep over the wheel 67. Then a spring 80 will bring the wheel 64 back again into its normal position.

The dial 22 is screwed into a bezel 81 which is fitted to the base plate 1 and held fast by means of two screws 82.

The golf-scorer has eighteen windows corresponding to as many holes and marked with numerals indicating the number of each hole.

Inside the windows appear numerals, which are

intended to mark the number of strokes employed for each hole.

Besides, the numerals on the windows of the large dial serve for totalizing the tens, while the numerals of the small dial serve for totalizing the units.

By turning the knob on stem 12 the hand 23 is moved to mark a hole, but it must be borne in mind that (on account of the pin 48 in Fig. 3) the stem cannot be turned backwards if by mistake the hand has been turned too far and has already passed the number of the next hole.

At the beginning of the game if every window and hand is at zero, turning the knob from right to left will put the large hand upon the numeral 1 to mark the first hole. This rotation of the stem 12 will cause plate 18 to move until the pawl 51 is in a position to engage the ratchet teeth in the wheel 3 which indicates the number of strokes for the first hole.

When in this position, each depression of the knob of stem 12 will cause a movement of pawl 51 which, in turn, will rotate wheel 3 one notch. As hereinbefore described, a depression of stem 12 will effect a rocking of lever 34 and this, in turn, will transmit motion through link 32 to pin 28 and will cause pin 28 carried by wheel 27 to move from the full line position in Fig. 2 to the dotted line position. This effects rotation of wheel 27 a distance equal to one notch.

Since pin 48 of arm 47 is in one of the notches of wheel 27, arm 47, which serves as a link and which is pivoted at 46 to one end of the rocker arm or swivel 45, will cause the arm 45 to rock about the pivot 44. Rocking of swivel 45, because of the pin and slot connection 52-53, will cause sliding of the pawl 51 and the turning of wheel 3 one notch.

After the necessary strokes for completing the playing of the first hole have been registered, the stem 12 is rotated to cause the plate 18 to rotate until the spring pawl 21 (Fig. 3) falls into the next notch of wheel 20, at which position pawl 51 will be arranged to engage the notches 110 in wheel 3 for indicating the playing of the second hole. When the plate 18 and the mechanism carried thereby are so adjusted, then each depression of the stem 12 will cause wheel 3 for the second hole to move one notch.

The same operation takes place for each hole played.

In addition to moving one of the wheels 3 for each depression of the stem 12, a totaling mechanism is operated, which indicates the total number of strokes played or the total number of depressions of the stem 12. The mechanism for accomplishing this result, as hereinbefore described and as clearly shown in Fig. 2, consists of the swivel 57 which is pivoted to the lever 34 by pin 58. A spring 63 serves to move the point of the element 57 into a notch of wheel 59. For each depression of the stem 12, wheel 59 is turned one notch and the pointer 66 is moved from one of the numerals on its dial to another.

A wheel 64 meshes with the teeth on wheel 59 and carries finger 65 which engages the notches in wheel 67. For each complete revolution of wheels 59 and 64, wheel 67 is moved one notch. Pointer 56 rotates with wheel 67 and after each ten depressions of the stem 12 the pointer 56 moves from one numeral to another.

After the game or desired number of holes have been played, all of the wheels 3 and pointers 56 and 66 may be restored to zero settings by

continuing to rotate the stem 12 until the plate 18 has made a complete revolution and the pointer 23 has returned to zero. Shortly after the pointer 23 has passed the zero hole on the zero 5 restoring movement, the pin 72 of the hammer 70 falls into notch 73 and the hammer 70 presses the heart cams on the wheels 59 and 67 to restore these wheels and the pointers carried thereby to zero settings. Also, as previously described, in making the zero restoring movement the cam 54 and spring 55 act on the hammers 10 engaging the heart cams of wheels 3.

After this operation is completed, the device 15 is again ready for use.

15 What I claim is:

1. In a watch-shaped golf-scorer having a dial with pointers and a circular series of small windows disclosing the numerals of numeral wheels the combination of a circular base plate having 20 radially arranged slots, numeral wheels mounted on axles within said slots in planes standing vertically on said base plate, said plate having a concentric circular notch cut into the teeth of the base plate left by said slots and adapted 25 to serve as bearings for the axles of the numeral wheels.

2. In a watch-shaped golf-scorer having a dial with pointers and a circular series of small windows disclosing the numerals of numeral wheels the combination of a circular base plate having 30 radially arranged slots and numeral wheels mounted on axles within said slots in planes standing vertically on said base-plate, a heart-cam and hammer device adapted to restore the 35 zero position of said numeral wheels and combined with these wheels, said plate having a concentric circular notch cut into the teeth of the base plate left by said slots and adapted to receive the axles of the numeral wheels, said plate 40

also having a similar circular notch adapted to receive the axles of the heart-cam hammers and a wire ring fitted into the last mentioned notch and forming the axles of said heart-cam hammers.

3. In a watch-shaped golf-scorer having a dial with pointers and a circular series of small windows for displaying numerals on numeral wheels, the combination of a circular base plate having a plurality of radially arranged slots formed in the edge thereof, said base plate having an annular groove formed in one face, wire-like means positioned in said annular groove adapted to serve as axle means for the numeral wheels. 80

3. In a watch-shaped golf-scorer having a dial with pointers and a circular series of small windows for displaying numerals on numeral wheels, the combination of a circular base plate having a plurality of radially arranged slots formed in the edge thereof, said base plate having an annular groove formed in one face, wire-like means positioned in said annular groove adapted to serve as axle means for the numeral wheels. 85

4. In a watch-shaped golf-scorer having a dial with pointers and a circular series of small windows for displaying numerals on numeral wheels, the combination of a circular base plate having a plurality of radially arranged slots formed in the edge thereof, said base plate having an annular groove formed in one face, wire-like means positioned in said annular groove adapted to serve as axle means for the numeral wheels, and means for detachably retaining the wire-like 90

means in the annular groove. 95

4. In a watch-shaped golf-scorer having a dial with pointers and a circular series of small windows for displaying numerals on numeral wheels, the combination of a circular base plate having a plurality of radially arranged slots formed in the edge thereof, said base plate having an annular groove formed in one face, wire-like means positioned in said annular groove adapted to serve as axle means for the numeral wheels, and means for detachably retaining the wire-like 100

means in the annular groove. 105

5. In a watch-shaped golf-scorer having a dial for displaying numerals on numeral wheels, the combination of a circular base plate having a plurality of radially arranged slots formed in the edge thereof, numeral wheels in said slots, zero-setting means associated with said wheels and positioned in said slots, said base plate having concentric annular grooves formed in one face thereof and wire-like means positioned in 110 said grooves, the wire-like means in one groove serving as axles for the wheels and the wire-like means in the other groove serving for pivotally mounting the zero-setting means. 115
